UNITED STATES PATENT OFFICE.

BROWN V. HALLGREEN, OF TRENTON, NEW JERSEY.

DESIGN FOR HOSE.

52,571.

Specification for Design. Patented Oct. 15, 1918.

Application filed November 4, 1916. Serial No. 129,455. Term of patent 14 years.

To all whom it may concern:

Be it known that I, BROWN V. HALLGREEN, a citizen of the United States, residing at Trenton, in the county of Mercer and State of New Jersey, have invented a new, original, and ornamental Design for Hose, of which the following is a specification, reference being had to the accompanying drawing, forming part thereof.

Fig. 2 is a vertical cross-sectional view thereof.

What I claim is:

The ornamental design for hose, as shown.

BROWN V. HALLGREEN.
